(57) **CLAIM**

I claim the ornamental design for a notebook cover, as shown and described.

DESCRIPTION

FIG. 1 is a perspective view of the notebook cover in an opened position;

FIG. 2 is a front view of the notebook cover in an opened position;

FIG. 3 is a rear view of the notebook cover in an opened position;

FIG. 4 is a rear view of the notebook cover in an opened position with environment removed in order to show aspects of the design not otherwise apparent;

FIG. 5 is a bottom view of the notebook cover in an opened position;

FIG. 6 is a top view of the notebook cover in an opened position;

FIG. 7 is a left side view of the notebook cover in an opened position;

FIG. 8 is a right side view of the notebook cover in an opened position;

FIG. 9 is a perspective view of the notebook cover in a closed position and locked state;

FIG. 10 is a front view of the notebook cover in a closed position and locked state;

FIG. 11 is a rear view of the notebook cover in a closed position and locked state;

FIG. 12 is a bottom view of the notebook cover in a closed position and locked state;

FIG. 13 is a top view of the notebook cover in a closed position and locked state;

FIG. 14 is a left side view of the notebook cover in a closed position and locked state;

FIG. 15 is a right side view of the notebook cover in a closed position and locked state;

FIG. 16 is a perspective view of the notebook cover in a closed position and unlocked state;
